UNITED STATES PATENT OFFICE.

JOHN SCHADE, JR., OF NEW YORK, N. Y., ASSIGNOR TO FAHNESTOCK ELECTRIC COMPANY, OF NEW YORK, N. Y., A CORPORATION OF WEST VIRGINIA.

DESIGN FOR A SPRING FASTENING DEVICE.

46,621.

Specification for Design.

Patented Nov. 3, 1914.

Application filed December 3, 1913. Serial No. 804,515. Term of patent 14 years.

To all whom it may concern:

Be it known that I, JOHN SCHADE, Jr., a citizen of the United States, residing in the borough of Brooklyn, county of Kings, city and State of New York, have invented a new, original, and ornamental Design for Spring Fastening Devices, of which the following is a specification, reference being had to the accompanying drawing, forming a part thereof.

The figure is a perspective view of a spring fastening device, showing my new design.

I claim:

The ornamental design for a spring fastening device, as shown.

In testimony whereof I have signed this specification in the presence of two subscribing witnesses.

JOHN SCHADE, JR.
